INCENDIARY BOMB CARRIER

Philip E. Willman, Hinsdale, Ill., assignee to
McGraw Electric Company, Elgin, Ill., a corporation of Delaware

Application March 21, 1942, Serial No. 435,685

14 Claims. (Cl. 294—55)

My invention relates to carriers for incendiary bombs.

An object of my invention is to provide a relatively simple and inexpensive carrier for a burning incendiary bomb.

Another object of my invention is to provide a relatively light-weight and easily manipulated device for picking up an incendiary bomb and transporting it to a place where its possible damage may be greatly reduced or possibly entirely prevented.

Another object of my invention is to provide a relatively simple light-weight and easily manufactured device for carrying an incendiary bomb with substantially complete safety to the carrier.

Other objects of my invention will either be apparent from a description of one form of such device embodying my invention and now preferred by me or will be pointed out in the course of such description and set forth more particularly in the appended claims.

In the drawings,

Figure 1 is a top plan view of a device embodying my invention,

Fig. 2 is a side view of the device shown in Fig. 1,

Fig. 3 is a cross-sectional view taken on the line 3—3 of Fig. 1, showing the parts in certain positions;

Fig. 4 is a cross-sectional view similar to that of Fig. 3 except that the carrier parts are shown in different positions.

Fig. 5 is a cross-sectional view similar to that of Fig. 3 but showing the parts of the carrier in bomb-carrying positions.

Fig. 6 is a cross-sectional view similar to that of Fig. 5 but showing the parts of the carrier casing under certain possible abnormal conditions.

Fig. 7 is a fragmentary end view of a modified form of carrier embodying my invention, and,

Fig. 8 is a fragmentary view, in front elevation of the device shown in Fig. 7.

It has been found highly desirable, in the manufacture of incendiary bombs, to have available relatively simple means permitting of easily and quickly picking up an ignited and burning incendiary bomb to enable an operator to carry it to some other place, such as outdoors, where it may continue to burn and possibly explode without appreciable danger of setting fire to other objects, such as buildings.

The same general remarks apply, of course, to cases where incendiary bombs are dropped as from an airplane and it is desired to easily and

quickly pick up such bombs from the place or places where they may have landed and move them to some other place, such as outdoors, where the damage which they may cause may be either greatly reduced or possibly completely prevented.

The device embodying my invention comprises more particularly a substantially straight carrying-handle 11 which may be made of any suitable material and has so far been made of wood. I prefer to make the shape, in cross-section, of the handle other than circular and thus far have found it advisable to make it substantially of square lateral section so that an operator can hold the bomb-carrying parts properly in desired positions.

At one end of the handle 11 I provide a forked casing support comprising two metal bars 13, each of which are generally of Z-shape, having one end portion of each bar connected to the end portion of the handle by clamping bolts 15 or by any other suitable means which will hold the forked support fixedly at the end of the handle 11.

I provide a casing for receiving, enclosing and carrying an incendiary bomb, this casing consisting of two semi-tubular parts 17 and 19. I may make the parts 17 and 19 of sheet metal of suitable thickness and at present I prefer to make the members 17 and 19 of pieces or sheets of thin metal rolled to the desired radius.

Member 17, which constitutes the top part or cover of the casing, is pivotally supported from the fork consisting of the two bars 13, whose outer ends are spaced apart, as shown more particularly in Fig. 1 of the drawings, and I provide two arms 21 extending laterally from the cover part 17, each of these arms having secured thereto or integral therewith a flange portion 23 to permit of securing the spaced arms 21 to the cover 17, in a manner shown in Fig. 1 of the drawings.

The bomb supporting or carrying part 19, which may also be termed the lower part, is pivotally supported from the upper or cover part 17 as by lugs 25 which are so designed and constructed that they may be rigidly secured to member 19. It will be noted that I provide bolts or rivets 27 to pivotally connect the outer ends of the respective arms 13 and the cooperating arms 21 secured to the cover 17 and that I provide bolts or rivets 29 to pivotally connect the lugs 25 with the respective lugs 21. It will be noted that the pivotal supports comprising the rivets or bolts 27 and 29 are aligned with one diameter of the bomb-carrying case constituted by the lower part 19 and the cover 17. It will

be noticed that the two parts of the casing are normally swinging in closed position, especially when the handle is in substantially horizontal position.

In order to permit of effecting pivotal swinging or turning movement of the casing which extends laterally of the axis of the handle 11, I may provide arms 31 and 33 extending laterally relatively to the casing and having a flange portion 35 and 37 secured thereto or integral therewith whereby the arms 31 and 33 may individually be connected rigidly to the lower member 19. The flange portions 35 and 37 may be secured to the member 19 in any suitable or desired manner, such as spot welding. Instead of using two such arms, I may use only one arm.

Means for causing opening and closing movements of the two casing parts and for also causing swinging or turning movement of the casing relatively to the axis of the handle and on its support are provided and include a link 39, one end of which is pivotally connected to the two arms 31 and 33 as by a bolt 41. The other end of the link 39 is pivotally connected to a manually-actuable over-center lever arm 43 one end of which is pivotally supported as by a lug or support 45 fixedly mounted on the handle 11. When the lever arm 43 is in a position substantially mid-way between its extreme turning positions to the right and to the left, which position is shown in full lines in Fig. 2 of the drawings, the casing is in substantially closed position assuming that the position of the handle 11 is substantially horizontal or extends at only a slight angle below a horizontal position.

If the lever arm 43 is turned to the right until its outer end rests against or is close to one surface of the arm 11, which position is shown at 47 in Fig. 2 of the drawings, the casing parts 17 and 19 will have been moved to substantially the positions shown in Fig. 4 of the drawings. If the operator then moves the lever arm 43 to its extreme left-hand position, as shown at 49 in Fig. 2 of the drawings, the casing portions will have been moved to substantially the positions shown in Fig. 5 of the drawings, that is, the two casing parts have been moved to engaging or closed position and the casing in its closed position has been moved to a position where its longitudinal axis lies substantially in the same plane as the plane of the axis of the handle, all as shown in Fig. 5 of the drawings. It will be further noted that the connection between the link 39 and the manually-actuable lever arm 43 is such as to provide over-center and locked positions when the lever arm 43 is in its opposed or limiting operative positions, as hereinbefore described, so that undesired or accidental movements of the casing parts either relatively to each other or to the carrying handle will be effectively prevented.

The casing member 17 is provided with a substantially semi-circular end closure member 51 at each end of the sheet metal part 17 and the lower member 19 is provided with a substantially similar semi-circular end closure member 53 which closure members may be brazed or welded, such as by spot welds, to the sheet metal casing portions 17 and 19.

Members 51 closing the ends of the cover part are provided with openings 55 for ventilating and cooling purposes.

The cover part of the casing may have located therein a lining 57 which may be of any high temperature resisting refractory material or may

be made of suitable asbestos. The lower portion 19 may be provided with a relatively thick layer 59 of a high-temperature resisting refractory material, such as fire clay or magnesite, and any suitable or desired means or method of inserting the lining 57 and of thereafter holding it in its proper operative position may be employed by me.

I provide further linings of heat-conducting material, preferably of a metal having a relatively high melting point, in each of the two portions 17 and 19 and have indicated such strip or sheet of metal by the numerals 61 and 63. The object of this is to provide means for distributing the highly localized heat generated by a burning or ignited incendiary bomb so as to reduce the heat effect of a burning bomb on the linings 57 and 59.

I wish to call attention also to a small lug 65 constituting a part of the lug or arm 21 at one side of the casing and the carrier structure in order to prevent excessive turning movement of the upper part or cover of the casing on its pivotal supports 21, in a clockwise direction.

Referring now to Figs. 7 and 8, I have there shown another means which I may use to swingingly support the casing portion 19 from the other casing portion 17. Instead of using lugs and pivot pins I may use springs 67, of substantially U-shape having their ends suitably secured to the casing parts 17 and 19. These springs are so shaped as to normally hold the casing parts 17 and 19 in closed position, turning movement of lever arm 43 in a clockwise direction (as seen in Fig. 7) being necessary to move part 19 into the open position relative to part 17.

Let it be assumed that a burning incendiary bomb, designated by the numeral 69 in Fig. 4 of the drawings, is resting on some supporting surface. An operator will take hold of the handle 11 and manually move the lever arm 43 in a clockwise direction to the position shown by the numeral 47 in Fig. 2 of the drawings, which will result in spreading the two parts of the normally-closed casing far enough apart to permit of moving the spread parts of the casing over the bomb and the operator can, by pulling on the handle in such direction as to slightly move the casing towards himself, cause the casing to substantially cover, at least from the top, the bomb 69. Manual turning movement of the lever arm 43 in a counter-clockwise direction and to the position 49 of Fig. 2 will cause first an approaching or closing movement of lower part 19 towards the cover 17 and when arm 43 is in substantially its mid position, shown in Fig. 2 of the drawings, the casing parts will occupy the position shown in Fig. 3 of the drawings when the bomb 69 will be substantially completely enclosed and therefore rendered, at least temporarily, substantially unable to do any appreciable damage.

Further turning movement of lever arm 43 in a counter-clockwise direction and to its limit as indicated by numeral 49 in Fig. 2 of the drawings, will result in causing pivotal or turning movement of the casing into substantially the position shown in Fig. 5 of the drawings where the longitudinal axis of the casing is substantially in the plane of the longitudinal axis of the handle. It may be pointed out that no leakage of molten material of the bomb can now occur and the carrier may be left in this position and the bomb permitted to burn out in the carrier

with only relatively slight possible and easily repaired damage to the carrier.

In the case of certain incendiary bombs, it may happen that an explosion of the bomb may occur before the person carrying it has deposited it in a place where any damage which may be done thereby is greatly reduced and the structure embodied in my device permits of easy and quick relief of the excess pressure in the hollow casing. I have shown these positions, particularly of the casing parts, in Fig. 6 of the drawings from which it will be noticed that the pivotal supports constituted by the pins 29 have been turned in a counter-clockwise direction to permit of the opening movement of cover portion 11 to the position shown in Fig. 6 of the drawings. It is obvious that as soon as the pressure of such explosion has been relieved, in the manner set forth above, the parts of the casing will return to the positions shown in Fig. 5 of the drawings. It is also obvious that the ventilating openings 55 will be of help in relieving the excess gas pressure during such explosion.

It is also possible that some of the molten metal generated or produced by the burning or exploding bomb may reach the edges of the sheet metal members 17 and 19, these edges being the lower ones shown in Figs. 3 and 4. In order to prevent melting of these edges and possible welding thereof with a resultant permanent closure of the casing, I prefer to cut back the edges as shown at 69 and 71 in Figs. 3 and 4 of the drawings. In other words, any molten metal will engage the edges of the lining 57 and of the lining 59 rather than the edges of the sheet metal strip of the casing.

Tests made with a device of this kind on burning incendiary bombs have demonstrated that even an inexperienced operator can easily and quickly pick up such a bomb and carry it outside a building or to some place where the damage which may be caused thereby will be greatly reduced.

I may also point out that a fire warden having one of these carriers available for use may also pick up and dispose of burning embers falling on a roof because of a fire or an explosion in a nearby building or structure, my device grasping and holding such burning pieces even though it cannot enclose them if they are too large.

Various modifications may be made in the structures embodying my invention and all such modifications clearly coming within the scope of the appended claims are to be considered as being covered thereby.

I claim as my invention:

1. A carrier for an incendiary bomb, comprising a longitudinally-split two-part tubular casing, means on one of said parts for movably supporting the other part of the casing, a handle supporting said casing for relative movement therebetween, an arm secured to said other part of the casing and manually operable means on said handle operatively connected to said arm for causing opening and closing movements of both said casing parts.

2. A carrier for an incendiary bomb, comprising a handle, a forked support at one end of the handle, a longitudinally-split two-part tubular casing, means secured to the casing for supporting the casing from said forked support for movement relative to the handle, an arm secured to said casing and projecting laterally therefrom and means on said handle operatively connected

to said arm for causing opening and closing movements of said casing parts.

3. A carrier for an incendiary bomb, comprising a handle, a forked support at one end of the handle, a longitudinally-split two-part tubular casing, means secured to the first part of said casing for movably supporting the casing from said forked support, means on the second part of the casing for supporting said second part on said first part for relative movement therebetween, an arm rigidly secured to said second part of the casing and extending laterally therefrom and a manually-actuable linkage on said handle operatively connected to said arm for causing reversible movement of said second casing part relative to said first casing part and swinging movement of both said casing parts simultaneously on said forked support.

4. A carrier for an incendiary bomb comprising a longitudinally-split two-part tubular casing, a handle, means for swingingly supporting the casing on said handle, means including a lever arm pivotally mounted on said handle and a linkage operatively connecting the lever arm and the casing for causing opening and closing movements of said casing parts relative to each other and swinging movement of said casing relative to said handle and to hold the casing in closed condition in a fixed position relative to said handle.

5. A carrier for an incendiary bomb, comprising a substantially straight handle, a tubular casing having upper and lower parts connected for movement relative to each other and extending laterally of the handle, means pivotally supporting the upper casing part on said handle, an arm extending laterally of the casing and having one end rigidly secured to the lower casing part and means including an over-center lever arm pivotally mounted on the handle and a link connecting said lever arm and said arm to cause movement of said lever arm in one direction into locked position to move the two casing parts into open condition and movement of said lever arm in the other direction into locked position to move the two casing parts into closed condition and then into a fixed position relative to said handle.

6. A carrier for an incendiary bomb comprising a handle, a tubular casing having a lower bomb-supporting part and an upper cover part, means pivotally supporting the cover part from said handle, an arm having one end rigidly secured to said lower bomb-supporting part and extending laterally therefrom and manually-actuable means on said handle operatively connected to said arm to cause opening and closing swinging movements of said casing portions, to cause pivotal turning movement of the entire casing relative to said handle and to hold the entire casing in closed condition in a fixed position relative to said handle.

7. A carrier for an incendiary bomb comprising a substantially straight handle, a tubular casing including a lower bomb-carrying part and an upper cover part and extending laterally across the axis of said handle, means pivotally supporting the cover part from said handle, an arm having one end rigidly secured to the lower bomb-carrying part and extending laterally therefrom and means including a manually-actuable lever arm pivotally mounted on said handle and a linkage connecting said arm and said lever arm to cause pivotal movement of said lever arm in one direction to effect opening movement of the casing parts and pivotal movement of said lever arm in the other direction to effect closing movement

of the casing parts, turning movement of the entire casing until the axis of the casing is substantially in the same plane as is the axis of the handle and to then hold the lower casing part substantially rigidly relatively to the handle.

8. A carrier for an incendiary bomb comprising a lower semi-tubular bomb-supporting member, an upper semi-tubular cover member, a handle connected to said cover member for effecting relative swinging movement therebetween, a lining of high temperature resisting refractory material in said lower member and means on said refractory lining to distribute the normally localized heat from a burning incendiary bomb in said lower semi-tubular bomb-supporting member.

9. A carrier for an incendiary bomb comprising a handle, a longitudinally-split tubular casing including a semi-tubular lower bomb-supporting member, a semi-tubular cover member, a lining of high-temperature resisting refractory material in said lower member and a sheet of metal on said lining to distribute the normally localized heat from a burning incendiary bomb in said lower member.

10. A carrier for an incendiary bomb comprising a handle, a longitudinally-split tubular casing including a semi-tubular lower bomb-supporting member, a semi-tubular cover member, a lining of high-temperature resisting refractory material in said cover member and a sheet of metal on said lining of refractory material to distribute the normally localized heat from a burning incendiary bomb in the lower member.

11. A portable carrier for an incendiary bomb comprising a handle, a two-part basket pivotally supported by said handle, the two parts being in closed position when the handle is held in its normal bomb-carrying position, a lever arm secured to one of the parts of said basket and extending laterally away therefrom, a link connected to the outer end of said lever arm and means on said handle connected to said link to cause pivotal opening and closing movements of both parts of said basket.

12. A portable carrier for an incendiary bomb comprising two semi-tubular members, a handle pivotally connected to said carrier and means on

5 said handle for causing opening and closing movements of both of said carrier members relative to each other and for holding said two carrier members in fixed position relative to said handle when carrying a bomb in said carrier.

13. A carrier for an incendiary bomb comprising a handle, a longitudinally-split tubular casing swingingly supported by said handle and including a semi-tubular lower bomb-supporting part and a semi-tubular cover part, the two parts tending to remain in closed position when the handle is held in its normal bomb-carrying position, an arm having one end secured to the lower part of the casing, manually-operable means connected to said arm to cause opening movement of said lower part of the casing to pick up a bomb, to then cause said lower part of the casing to swing relative to said handle into a position to cause the bomb to rest in the lower part of the casing, the cover part of the casing being then free to move away from the lower part of the casing in case of an explosion of the bomb in the carrier.

14. A carrier for an incendiary bomb comprising an elongated handle, a longitudinally-split tubular casing, the axis of which extends laterally of the handle, and including a cover part and a lower bomb-supporting part, means for swingably supporting the cover part from the handle, means for swingably supporting the lower part from the cover part, the two parts of the casing tending to remain in closed position when the handle is held in substantially horizontal bomb-carrying position, manually-operable means connected with said lower bomb-carrying part to cause opening movement of said casing parts to pick up a bomb, to then cause closing movement of said casing parts and to then cause swinging movement of said closed casing relative to said handle into a fixed position relative thereto to cause the bomb to rest in the lower part of the casing when the handle is held in substantially horizontal position, the cover part of the casing being then free to move away from the lower part of the casing in case of an explosion of the bomb in the carrier.

PHILIP E. WILLMAN
